[57] CLAIM

The ornamental design for a table top for massaging and chiropractic therapy, showing our new design.

DESCRIPTION

FIG. 1 is a front, top and left side perspective view of a table top for massaging and chiropractic therapy showing our new design;

FIG. 2 is a front elevational view thereof;

FIG. 3 is a top plan view thereof;

FIG. 4 is a left side elevational view thereof;

FIG. 5 is a right side elevational view thereof;

FIG. 6 is a bottom plan view thereof;

FIG. 7 is a front, top and left side perspective view of a modified form of FIG. 1, the only difference residing in the appearance of the top.

FIG. 1

FIG. 2

FIG. 3

FIG. 4

FIG. 5

FIG. 6

FIG. 7
